EDWIN R. GILL, OF YONKERS, NEW YORK, ASSIGNOR, BY MESNE ASSIGNMENTS, TO
HALL SWITCH & SIGNAL COMPANY, A CORPORATION OF MAINE.

SELECTIVE SIGNALING APPARATUS.

1,137,475.

Specification of Letters Patent. Patented Apr. 27, 1915.

Application filed March 28, 1912. Serial No. 686,798.

To all whom it may concern:

Be it known that I, EDWIN R. GILL, residing at Yonkers, in the county of Westchester and State of New York, have invented 5 certain new and useful Improvements in Selective Signaling Apparatus, of which the following is a specification.

This invention relates to high speed selectors for use on telephone and telegraph lines, 10 whereby signals at different points along a line may be selectively operated without interference by electrical impulses impressed upon the line, the several selectors being preferably controlled as by means of an automatic sender wherein a movable contact is impelled forward rapidly step by step. By pausing after the appropriate forward step, 15 the operator is able to cause the operation of the selector at a given station, thus calling that station without disturbing any other upon the line. A great difficulty in the use of selectors as hitherto constructed has been that the selectors could not be returned to normal save by stepping them up through 20 their appointed phase of movement. Accordingly, if the first selector, for instance of a series, were operated, in order to bring all the instruments to normal, the actuating impulses would have to be continued until 25 all, even the very last of the selectors, had completed their appointed phase and been returned to the normal condition necessary to proper operation.

The present invention which involves certain improvements over the structure covered by my co-pending application for selective signaling apparatus, Serial No. 588,359, therefore contemplates a change in the construction of selectors of the kind referred to 35 whereby at the end of a predetermined time after impulses used for operating the selector or selectors have been impressed upon the line, a controlling element comes into operation in such a way that all the selectors will automatically return to normal, whether or 40 not their operative phases have been completed.

Another object of the invention is to improve upon the construction of the selector whereby the operation is rendered more positive and certain.

Other objects and aims of the invention will be more specifically pointed out in the course of the following description of the 55 features of construction, arrangements of

parts and combinations of elements, and the scope of protection contemplated will be indicated in the appended claims.

In the accompanying drawings, which are to be taken as a part of this application, and in which I show a preferred embodiment of the invention: Figure 1 is an elevation of one side of the selector; Fig. 2 is a similar view of the opposite side of said device; Fig. 3 is a top plan view of said device; Fig. 4 is a vertical sectional view taken on the line 4—4 of Fig. 3; Fig. 5 is a view in elevation of a ratchet wheel adapted to be stepped up by electrical impulses; Fig. 6 is a fragmentary view in plan taken substantially on the line 6—6 of Fig. 4; Fig. 7 is a view in front elevation of the selector; and Fig. 8 is a sectional view taken substantially on the line 8—8 of Fig. 3.

Referring to the numerals on the drawings, 1 indicates a base member, which is adapted to support a casing inclosing the selector, the frame-work of which is shown at 2. This frame-work supports a horizontal shaft 4 upon which is carried a ratchet wheel 5, which is normally impelled in the direction of the arrow, Fig. 4, by the spiral spring 6. An electro-magnet 7 acts through the armature 8, bowed spring 9, and connecting rod 10 to operate an impelling lever 11. An impelling pawl 12 is pivoted to the end of the lever 11 and is provided with an arm 14 against which bears the spring 15. The function of this spring is to direct the lower end of the pawl into the successive teeth on the wheel 5. A stop 16 is provided to limit the downward movement of the pawl 12. Whenever the energization of the magnet 7 permits the lever 11 to swing downward on its pivot 17, the impelling pawl 12 will engage the ratchet wheel 5 and move the same one tooth forward. When the electro-magnet 7 is deenergized, the spring 9 causes the lever 11 and with it the pawl 12 to rise. When this motion takes place, a retaining pawl 18 on a pivoted arm 19 acts on the teeth of the ratchet 5 to prevent return to normal under the influence of the spring 6.

For reasons hereinafter explained, the arm 19 is carried upon an inclined shaft 20 rotatable in opposite side pieces of the frame, said shaft being movable endwise upon its journals whereby the pawl 18 may be disengaged from the wheel 5 upon longitudinal movement of the shaft 20. The inclination 110

of the shaft 20 facilitates the return of the pawl 18 into engagement with the wheel 5 as hereinafter explained, and also tends to keep the pawl always over the wheel 5 when it is intended that it should be there. It is desirable that the action of the wheel 5 and its driving parts should be substantially as follows:

When the wheel 5 is at normal and before any call is begun, it is intended that any rapid impulses should produce only a back and forth motion of said wheel through a space of one tooth, but that when a call is to be begun a long pause should prepare the wheel 5 for action and that thereafter a series of rapid impulses should cause the wheel to move forward step by step, without backward movement, until the phase of movement of the wheel has been completed.

In the present instance, the wheel 5 is provided with two types of teeth which may be designated "upper contact" and "lower contact" teeth. That is, certain of the teeth are beveled off at the top so that only the lower portions or bases of the teeth will operate to effect a positive holding engagement with the pawl 18 whereby the wheel 5 will be held against returning and others of said teeth are beveled off at the bottom whereby only the upper portions of said teeth will effect a positive holding engagement with the pawl 18, whereby the wheel 5 will be also held against returning. These teeth are indicated at 5¹ and 5², (see Fig. 5)

the numeral 5¹ indicating the "upper contact" teeth and the numeral 5² indicating the "lower contact" teeth. There is also provided upon the wheel 5 a tooth 5³, the upper end of which is cut off, and a tooth 5⁴ which is beveled both top and bottom, so that no portion of said tooth will operate to effect a holding engagement with the pawl 18.

Fig. 4 shows the normal position of the wheel 5 and the lever 19, and in this position the lever 19 is supported in an elevated position with the pawl 18 out of engagement with the wheel 5, a catch 21 on the lever 19 resting upon a hook 22 which is fixed upon a rock shaft 23. This hook, by its engagement with the catch 21, holds the pawl 18 in such position that while it will engage the "upper contact" teeth 5¹ of the wheel 5, it will not engage the cut-off tooth 5³ or the "lower contact" tooth 5², and inasmuch as the wheel 5 is normally held in such position that an actuation of the pawl 12 will only operate to move the tooth 5³ in front of the pawl 18, when the impulse 60 which has actuated the pawl 12 terminates, the wheel 5 will return to normal. Thus, rapid impulses will produce only a back and forth motion through the space of one tooth of the wheel 5. In order to cause the wheel 5 to progress its whole intended phase means

are provided whereby pause of sufficient duration occurring while the pawl 12 is depressed causes the pawl 18 to be dropped upon the wheel into position to engage the base of the tooth 5³, and also the bases of the "lower contact" teeth 5². For this purpose the following means are employed.

Upon a shaft 27 there is fixed a lever 28 to the outer extremity of which is pivoted a frame-work 29, carrying an inertia wheel 30, the hub 31 whereof rests upon an inclined track 32, and is adapted to slide or roll thereon. This wheel is held near the upper end of the track 32 by the arm 34, fixed upon the lever 11. Thus each time the impelling pawl is depressed the wheel 30 will begin to roll slowly down the track 32, and whenever the pawl 12 rises the arm 34 causes the wheel to slide quickly back upon the track 32. If the impelling pawl is depressed long enough, the wheel 30 will roll down the track 32 far enough to permit the frame-work 29 to engage a lever 35 fixed upon the revoluble shaft 23 to which the hook 22 is affixed. This action pushes the hook 22 rearwardly away from under the catch 21, thus releasing the pawl 18 and permitting it to fall upon the wheel 5, and into engagement with the lower portion of the cutaway tooth 5³, whereby the wheel 5 will be held against return movement. It will be noted that in the present arrangement the cutaway tooth 5³ is followed by five "upper contact" teeth. Therefore when the pawl 12 again descends to step the wheel 5 forward one tooth, the first of the "upper contact" teeth will lift the pawl 18 above the hook 22, which meanwhile has returned to normal position, whereupon the pawl dropping upon said hook will also drop behind the first of the "upper contact" teeth 5¹, thereby holding the wheel 5 against return movement. Five successive quick impulses will therefore cause the wheel 5 to be advanced. Inasmuch, however, as the tooth 5² is a "lower contact" tooth the succeeding impulse after the fifth quick impulse must be a long impulse to permit the frame 29 of the inertia device to engage the lever 35 whereby the hook 22 will be moved rearwardly, permitting the pawl 18 to drop into engagement with the base of the tooth 5², such operation maintaining the wheel 5 against returning. When the wheel 5 is again stepped forward by the descent of the pawl 12 the next tooth, which is an "upper contact" tooth, will again lift the pawl so that the catch 21 will rest upon the hook 22, also allowing it to fall into engagement with said tooth to hold the wheel. Therefore, one additional quick impulse will step the wheel forward. The next tooth 5¹, it will be understood, is beveled both top and bottom. Therefore, upon the next impulse, the pawl 12 must be held in its downward

position, since the parts have now been moved to a position which will close a contact to operate the electro-magnetic signal as will hereinafter be explained. When the 5 pawl 12 returns to normal position, the beveled portion of the tooth 5⁴ will push the lever 19 laterally, whereby the pawl 18 will be entirely disengaged from the wheel 5, allowing the latter to return to normal. It 10 follows, therefore, that the wheel 5 may be stepped forward by a predetermined series of impulses which follow each other quickly or with intermediate pauses until the inclined tooth 5⁴ comes in contact with the 15 pawl 18, such tooth due to the tendency of the wheel to return to normal under the influence of the spring 6, by a camming action, causing the lever 19 and the pawl 18 to move laterally so as to release the wheel 5.

20 An illustrative object of the entire device is to cause the closing of a normally opened circuit, and this end is attained as follows: A spring contact arm 38 is secured to the shaft 27 whose rotative movements, as will 25 be understood, are governed by the operation of the wheel 30, and coöperating with this arm 38 is an opposed arm 41, which is held upon and insulated from the machine frame by means of spaced insulating block 39, carried upon the upper portion of one of the side pieces of the frame. The arm 41 is connected as by means of the wire 40 to the binding post 44, the other of said binding posts 45 being grounded to the frame of 35 the machine. Thus when the contacts carried by the arms 38 and 41 are brought into engagement, a circuit will be closed through the binding posts 44 and 45, which circuit is intended to include the electro-magnetic signal 40 which is to be selectively operated. It will be seen therefore, that inasmuch as the movable contact arm 38 is carried upon the shaft 27, when the inertia wheel 30 rolls down the inclined track 32, the movement of 45 the arm 28 will cause shaft 27 to be rotated to bring the contact arms 38 and 41 into engagement.

In order to prevent a premature engagement of the arms 38 and 41, such as might 50 occur during an intermediate pause in a series of coded impulses, the shaft 4 is provided with a wheel 46 which is provided with a notch 47, which when the toothed wheel 5 has been stepped through its phase of movement will be carried immediately beneath a depending portion 48 of the contact arm 38 which will thereby allow the arm 38 to descend far enough to engage with the arm 41 to close the circuit. Such an intermediate 55 pause as has been described will permit the inertia wheel 30 to carry the arm 38 only far enough to allow the depending portion 48 to engage with the periphery of the wheel 46, thereby preventing a premature engagement 60 of the contact arms 38 and 41. There is

also fixed upon the shaft 4 an arm 24, which when the toothed wheel is returned to normal by its spring, will strike the inclined forward face of the lever 19 and raise the catch 21 upon the hook 22, the lever 19 having previously been moved laterally out of engagement with the wheel 5, and the inclined pin 37 on the wheel 5 will thereupon engage with the lever 19 and aid in its lateral movement to a position immediately above the wheel 5. 70

I have also provided means whose function is to return the wheel 5 to normal position automatically in a case where said wheel has not been progressed sufficiently to bring its inclined tooth 5⁴ into action, upon the 80 happening of a break in the line or upon the end of a predetermined time after impulses used for operating the selector have been impressed upon the line. To this end I have provided upon the opposite side of the frame 85 from that occupied by the timing wheel 30 a second timing wheel 49 which controls means for returning the wheel 5 to normal as stated. This timing element comprises an arm 50 fixed upon a shaft 51 journaled 90 at the side of the machine frame, and to whose outer end is pivoted a frame-work 52 carrying a hub 54, and the wheel 49 similar to that already described upon the opposite side of the machine. The hub 54 runs 95 upon a track 56 whose inclination to the horizontal is opposite to that of the track 32. The wheel 49 is adapted to be slid upon this track by means of an arm 57, that is secured to the forward end of the lever 11, so that upon each downward movement of 100 the impelling pawl 12 the timing wheel 49 is slid upward upon its track. When the impelling pawl rises upon the deenergization 105 of the magnet 7, the timing wheel 49 will begin to roll slowly down its track, and if this movement is allowed to continue to a sufficient extent, the wheel 5 will be released from any engagement which it may have with the pawl 18 in the following manner.

A lever 58 (see Fig. 6) is carried upon a suitable bracket 59, formed upon the inner side of one of the side pieces of the machine frame so that it may have a free swinging movement. One end 60 of this lever is in horizontal alignment with a forward extension 61 of the lever 19 when the pawl upon said lever is in engagement with the wheel 5. The opposite end of lever 58 is provided with a bifurcated portion 62, which straddles a cross member 64 of the framework 52. When, upon depression of the pawl 12, the wheel 49 is moved upward upon its track, the bifurcated portion 62 of the lever 58 is engaged by the member 64 and said lever is 115 swung upon its bearings in such a way as to move the end portion 60 laterally away from the forward extension 61 of the lever 19. When there is a break in the circuit of a certain extent, or at the end of a predetermined 120

time after impulses used for operating the 5 selectors have been impressed upon the line, that is to say, the pawl 12 has been allowed to rise and there is no succeeding downward movement of the pawl for a certain period of time, the timing wheel 49 will be free to roll down its track, and as it does so the part 62 of the lever 58 is engaged by the member 64 of the frame-work 52, which 10 causes the end 60 of said lever to move inward and engage the forward extension 61 of the arm 19, if the pawl 18 is in engagement with the wheel 5. This engagement with the arm 19 will move the same and its 15 shaft 20 laterally, thereby disengaging the pawl 18 from the wheel 5 which thereupon is returned to normal by its spring 6.

In order to permit the catch 21 to drop off from the hook 22 when the arm 19 is 20 moved laterally away from wheel 5, a cut-away portion 25 is provided intermediate the end of the catch.

The operation of my improved selector, 25 whereby a circuit is closed at a selective station, exclusively, is as follows: Supposing a group of stations to be provided upon a single line with a selector in each station, then the teeth upon each of the wheels 5 are arranged in such manner that each wheel 30 will be stepped forward by a series of codal impulses different from that of any of the others of said wheels. All of the instruments will be arranged in a well known manner so that their magnets are all energized 35 simultaneously by impulses impressed upon the line. Supposing now that the station in which the selector disclosed herein is located is to be exclusively called, the instruments all being in normal position, the operator 40 will first hold the circuit through all of the magnet 7, closed long enough to permit the timing element 30 to release the catches 21 from the hooks 22 so that the pawls 18 of all the selectors may engage with the first 45 tooth on the wheels 5. Six impulses will now be produced, the first five of which will be short, but the last must be long enough to allow the timing element 30 and its associated mechanism to remove the hook 50 from the catch 21, whereupon the pawl 18 will engage with the lower contact surface of the tooth 5². Then follows two other impulses, the first one of which is a quick impulse and the second one followed by a 55 pause with the circuit closed. The timing wheel 30 will then again be operated, but this time the slot 47 of the wheel 46 is immediately beneath the extension 48 of the contact arm 38, and the arm 38 will thereby 60 be allowed to contact with the arm 41. The circuit will therefore be closed and the signal operated. It will be apparent that the toothed wheels 5 of the other instruments of the various selectors will have either re- 65 turned to normal or not moved far enough.

Consequently only the instrument intended will be operated.

It will be apparent that by means of the provision of the second timing element that when one station is called it will not be necessary to impress any further impulses upon the line to clear the same inasmuch as that after a pause of predetermined length occurs with the circuit open, such second time element will go into operation and return 75 all of the instruments to normal.

As many changes could be made in the above construction and many apparently widely different embodiments of this invention could be made without departing 80 from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention, what I claim as new and desire to secure by Letters Patent, is:

1. In a device of the class described, in combination, a member adapted to be stepped to a predetermined point by a series of codal impulses of different characteristics, means opposing the stepping of said member, means whose operation is determined by impulse characteristic to render said last named means inoperative, means for restoring said opposing means to operative condition when the member has been stepped through its phase of movement, a circuit closer, and a time element for operating said circuit closer when said member has been stepped through its phase of movement.

2. In a device of the kind described, a member adapted to be stepped to a predetermined point by a series of codal impulses of different characteristics, means opposing the stepping of said member, means whose operation is determined by impulse characteristic to render said last named means inoperative, means for restoring said opposing means to operative condition when the member has been stepped through its phase of movement, a pair of opposed contact members, one of which is movable, and a time element for moving said movable contact member.

3. In a device of the kind described, a toothed member adapted to be stepped by a series of impulses of different characteristics, means opposing the stepping of said member, a pawl adapted to engage the teeth of said member to prevent operation of the opposing means, means whose operation is

determined upon impulse characteristic for bringing the pawl and toothed member into operative relation, and a pair of opposed contact members which are adapted to be moved into operative relation by said last named means.

4. In a device of the kind described, a toothed member adapted to be stepped by a series of impulses, means opposing the stepping of said member, a pawl adapted to engage the teeth of said member to prevent operation of said opposing means, a time element whose operation is determined by impulse characteristic for bringing about operative relation between the toothed member and the pawl, and a circuit closer adapted to be operated by said time element.

5. In the device of the kind described, a toothed member adapted to be stepped by a series of impulses, means opposing the stepping of said member, a pawl adapted to engage the teeth of said member to prevent operation of said opposing means, a time element whose operation is determined by impulse characteristic for bringing about operative relation between the toothed member and the pawl, a pair of opposed contact members, one of said contact members being movable and its movement being controlled by said time element, means whereby when the first named member has been stepped by a predetermined series of impulses, said time element will bring about an operative relation between said contact members, and means whose operation is determined by impulse characteristic for throwing the toothed member and pawl out of operative relation.

6. In a device of the kind described, in combination, a toothed member adapted to be stepped through a phase of movement, means opposing the stepping of said member, a pawl adapted to engage the teeth of said member and preventing an effective operation of the opposing means, means whose operation is determined by an impulse characteristic for bringing said toothed member and said pawl into operative relation, and a pair of opposed contact members, said last named means being also adapted by impulse characteristic to move said contact members into engagement.

7. In a device of the kind described, a toothed member adapted to be stepped, means opposing the stepping of said member, a pawl adapted to engage the teeth of said member to prevent the operation of said opposing means, means for normally holding said pawl in inoperative position, a time element adapted to bring said toothed member and pawl into operative relation, and a member carried by the toothed member adapted to engage with said pawl and throw it into engagement with the means which is adapted to hold the same in inoperative po-

sition, the operation of said member being effected when the toothed member returns to normal.

8. In a device of the class described, a toothed wheel adapted to be stepped to a predetermined point by a series of impulses, a shaft carrying said wheel, means opposing the stepping of said wheel, a time element, a circuit closer having a movable contact operated by said time element whereby said circuit closer is operated when said wheel has been stepped to the predetermined point, and means carried by said shaft for preventing the time element from operating said circuit closer until said wheel has been stepped to said point.

9. In a device of the kind described, a toothed wheel adapted to be stepped to a predetermined point by a series of impulses, means opposing the stepping of said wheel, a shaft upon which said wheel is mounted, a time element, a circuit closer comprising a pair of opposed contact members, one of which is moved into operative position by said time element whereby said circuit closer is operated when said wheel has been stepped to the predetermined point and a notched wheel carried by said shaft for preventing the time element from operating said circuit closer until the wheel has been stepped to said point.

10. In a device of the kind described, a toothed wheel adapted to be stepped to a predetermined point by a series of impulses, a shaft carrying said wheel, means engaging said shaft for opposing the stepping of said wheel and for returning the same to normal position when stepped, a time element, a circuit closer comprising a pair of opposed contacts, one of which is movable, said movable contact being operated by said time element whereby said circuit closer is operated when said wheel has been stepped to said predetermined point and means carried by said shaft adapted to be engaged by one of the opposed members of said circuit closer to prevent an operation of said circuit closer until said series of impulses has been completed, said means being provided with a cut-away portion which permits the engagement of the opposed contact members of said circuit closer when said series of impulses has been completed.

11. In a device of the kind described, in combination, a toothed member adapted to be stepped to a phase of movement by a series of impulses, a shaft upon which said toothed member is mounted, spring means engaging said shaft to oppose the stepping of said member, a pawl adapted to engage the teeth of said member to prevent said spring from returning said toothed member to normal, means for normally holding said pawl in inoperative position, a time element adapted to bring said toothed member and

pawl into operative relation, a member carried by said toothed member adapted to engage with said pawl and throw it into engagement with the means which is adapted 5 to hold it in inoperative position, a circuit closer comprising a pair of opposed contact members, one of which is movable, the movable one of said opposed contact members being connected with said time element, 10 means carried by said shaft for preventing an engagement of said opposed contact members until the phase of movement of said member to be stepped has been completed, said means being adapted to permit the engagement of said opposed contact members 15 when said phase of movement has been completed, a second time element adapted to disengage said pawl from the teeth of the member to be stepped, and means carried by said shaft adapted, during the return 20 of said toothed member to normal, to engage with said pawl and throw it into engagement with the means for normally holding it in inoperative position.

In testimony whereof I affix my signature in the presence of two witnesses.

EDWIN R. GILL.
